1.

Daniel Gerrish.

Seller's Patent. Patented July 2, 1836.

The Schedule referred to in these Seller's Patent and making part of the same, containing a description in the words of the said Daniel Gerrish himself, of his Improvement in the construction of vessels.

To all, whom it may concern. Be it known, that I, Daniel Gerrish of Boston, in the State of Massachusetts, have invented, certain improvements in the manner of constructing or building, vessels, which are applicable to Vessels of war, and those intended to navigate the Ocean, as well as to those employed upon rivers, or other waters, all which may be propelled by steam, or otherwise. And I do hereby declare that the following, is a full and exact description thereof, reference being had to the drawings, which accompany, and make a part of this specification.

And I do further declare, that although I have hitherto given certain general and particular, measurements, I have done so for the purpose of facilitating the description, only, and not with any view, or in any manner, to limit myself, in this respect, as much latitude may be allowed therein, whilst the principle of construction remains unchanged.

The accompanying drawings (figures 1 and 2), represent plans of the skeleton framing, of the vessel, or steam-boat, figure 2, being a side view, and are drawn on a scale of 1/8 of an inch to a foot, figures 3 and 4 are cross sections, just, forward and astern, the side, which is drawn to a scale of 1/8 of an inch to the foot. Fig. 5, shows the planking of the stern, the other figures will be referred to in their appropriate specifications.

The vessel is supposed to be 940 feet in length, 30 in width forward, and 35 at about six yards, astern.

The Improvement consists in, 1st, the manner of constructing, and connecting bottom, and sides, of the vessel, as it is thought, it will combine the greatest possible degree of strength, with the least possible weight of timber, to effect which, the lower part, or bottom, of the vessel, is composed of deep timber, in width about two feet, in thickness, four inches, extending in parallel lines, at the distance of one foot, each from another, the whole length of the vessel, figs. 1 & 2 a, a; a, a.

July 2, 1836

The lower half of these main timbers, are to be crossed, at right angles, at the same distance of one foot, from each other, by similar timbers, of one foot in width, halved and grooved into them. The lower edges of all which timbers, are to be shaped, as to cover the covering, which forms the bottom, of the vessel, and the upper edges, of said inner timbers, are to be squared, even between the main timbers, thus forming a series of eight cells, of one square foot, each diameter, see fig. 1, 2, 2.

The upper half, of the main timbers, are to be crossed, in a similar manner, at the distance of four feet, or immediately over every pair of the side timbers, in the lower series of cells, see sections b, b, b, b.

Additional timbers may be laid flatways, between each of these, as at fig. 3, a, at any angles, crossing each other, and being halved, and grooved into the main timbers, as seen at fig. 1, c, c, c, c, and (after the side timbers are framed into the hull, or bottom timbers,) these upper edges, of all the timbers, are to be planed over, thereby forming the flooring, of the vessel, and constituting a second series of cells, of one by four feet each, which may be made air tight, or a part of them finished, with hatchways, for the purpose of stowing ballast or cargo, see sections b, b, b.

2nd. The timbers which form the sides, and top frame, of the vessel, are framed in, and into, the cross timbers, of the bottom, and are strengthened, by an additional framing, of the lattice work, halved into them, and covered in the usual manner, by planks, and ceiling, see fig. 1, 2, 3, 3, d, d, d, d.

3rd. To give additional strength, and firmness, to the vessel, a frame attached at the distance of four feet, from each other, and laid its whole length, being joined into the timbers, of the bottom, and so formed, the sides of the vessel, at this space, occupied by the wheel, and the frames of the cabin, and upper works, as seen at fig. 2, & 3, c, c, c, c. The four feet space between this frame, and the sides, is to be intersected, in a similar manner, as may be desired.

4th. In order to establish a thorough system, of bracing, in every part, and direction, the timbers, which form the main deck, are also halved and grooved into each other, crossing at any angles, extending, and being fastened to, the side frames, nearly, 18 d, c, c, c, c.

5th. When building a Steam Boat, thus constructed, an additional middle, may be

July 2, 1836

a rudder, in a position on a shaft, which descends through an open trunk, or well, from the deck to the rudder, which will when required, secure a more perfect control over the direction of the vessel, and may be preserved from injury by being more or less covered, within the recess formed for that purpose, as seen at fig. 1, f, f.

6th. In steam vessels, designed for sea service, I propose to place a part of the paddle wheels, in a recess of four feet, formed in the sides of the vessel, allowing them to project six feet, they being ten feet wide, and twenty four in diameter, as at fig. 1, g. The lines c, c, show the vessel quando and ff, the sides of the vessel.

I propose also to place an additional wheel, in the stern, occupying the entire width of that part of the vessel, say 20 feet, in length, and 2.2 feet in diameter, as at fig. 1, h, h.

figs. 6, & 7, show the location of two horizontal Engines, with their guides, and each on a line, and connected by a shackle bar, with the crank of its upper jointed side wheel, and also by another shackle bar to the crank, on one end of the stern wheel shaft, this last, named shackle bar, being connected, to, or with, a cross head, by a guide rod, i, i, i, i.

The stern wheel, being thus connected, with the two cranks, on the outside, at right angles with the two cranks, of the other side, j, j, all the wheels, will be impelled in a ring, the full action of the engines, viz. as much as will be of the crank passing their head centres, as at any other part, or point, of the revolution. And also, when by the motion of the waves, either of the three wheels, has little or no hold upon the water, the whole power of both Engines will be exerted upon the inner, or side, wheels.

7th. I propose, when it is desirable, to place the chimney, or smoke pipe, horizontally along the sides, or gunwales of the vessel, allowing the smoke to escape, in the vicinity of the stern, or side, wheels, the action of which will be calculated to promote the draught, as fig. 7, h, h.

8th. I intend sometimes to form the covering of the bottom, instead of sheet iron, or other metal, instead of plank, which will secure most of the benefit arising from iron steam, & which, the cover, will be lighter, and, much more secure, from danger in case of break, or accident, as the water, would be confined to a comparatively small number of cells. When the vessel is intended to navigate shallow waters, the form of the bottom

July 2, 1836

should be nearly flat, as drawn at figs. 7 & 8, & 10.

What I claim as my invention, in the above described Boat or Vessel is, 1st
The manner of constructing or framing and connecting the bottom and sides of the
Vessel as fully described in specification, Article 12. 2d.

2d. The additional frame selected, and for the purpose set forth and described
in Art. 8, and h, in combination with the bottom, as in Art. 1, and 2.

3d. The use and construction of a second or additional board, in combina-
tion with a Boat or Vessel of this construction as shown in Art. 3.

The application or forming the bottom covering of sheet iron or other
metal without planking, confining my claim to its combination with the
sides of this construction, as in Art. 1.
